UNITED STATES PATENT OFFICE.

CYRENIUS LOSCH, OF SCHUYLKILL HAVEN, PENNSYLVANIA.

DUMP HOIST.

1,414,426.

Specification of Letters Patent.

Patented May 2, 1922.

Application filed September 13, 1920. Serial No. 409,954.

To all whom it may concern:

Be it known that I, CYRENIUS LOSCH, a citizen of the United States, residing at Schuylkill Haven, in the county of Schuylkill and State of Pennsylvania, have invented a new and useful Dump Hoist, of which the following is a specification.

This invention provides means for raising the forward end of a motor truck body 10 to any desired degree within its limit of action, for the purpose of unloading, and to speedily restore or lower said body to its normal position.

The object of the invention is to provide 15 a hoist of this character which is simple in construction, reliable in operation, cheap to manufacture, and readily applicable to any of the motor trucks now in use.

With these ends in view the invention 20 resides in the combination and arrangement of parts and in the details of construction hereinafter described and claimed, it being understood that, within the scope of what is claimed, changes in the precise embodiment 25 of the invention shown can be made without departing from the spirit of the invention.

In the accompanying drawings the preferred form of the invention has been shown.

In said drawings—

30 Figure 1 is a side elevation of a sliding gear transmission, of known make, and hence needing no particular description, showing the manner of connection therewith for the purpose of securing the power to operate 35 the hoist.

Figure 2 is a side view of the hoist with some parts shown in section and some in elevation.

Figure 3 is a partial transverse view showing the operative relation and connections 40 between certain of the parts.

Figure 4 is an enlarged section on line 4—4, Figure 3.

Figure 5 is an enlarged section on line 45 5—5, Figure 3.

Referring to the figures by characters of reference 1 designates the transmission gear casing, which for the purpose of the present invention has a small portion thereof removed forming an aperture 2 so as to allow 50 engagement and disengagement of the gear 3 mounted exterior to the main casing with one of the transmission gears, and preferably with the reversing pinion 4 as shown.

55 The gear 3 is provided with a collar or

sleeve 5 and is adapted to move endwise with respect to its supporting shaft 6. This gear is normally held out of engagement with the reversing pinion 4 by a coiled spring 7. An enclosing casing, not shown, provided 60 with bearings 8 and 9 for supporting the shaft 6, is secured to the main transmission casing 1 in any approved manner, protecting the gears against dust and dirt, and preventing the escape of lubricant through the 65 aperture 2. The short shaft 6 carries a sprocket wheel 10 located in the rear of bearing 9, and connected by chain 14 with another sprocket wheel 11 secured to a shaft 12. This shaft has a pinion 13 and is journaled in a bracket 15 mounted upon the side member 16 of the main frame of the truck. The rear bracket 17 is provided with a bearing 18 in alignment with bearing 19 in the front bracket 15, and these bearings 70 carry a shaft 20 upon which the internal gear 21 and winding drum 22 are mounted. The drum 22 and internal gear 21 are shown as one piece, but each may be separate and both secured together in any approved manner so that the rotation of the internal gear 75 also rotates the drum. The completed structure may turn on the shaft 20, or it may be rigidly secured to the shaft, and the shaft 80 rotate in the bracket bearings 18 and 19, as desired, the pinion 13 being in mesh with internal gear 21 for the purpose of driving the latter. A brake band 23 encircling the internal gear 21 is provided for checking or holding the drum 22 in any position whenever desired. One end of the brake band 23 is secured to the main frame 16 and the other end is carried through an aperture in the main frame and connected with a suitable 85 operating lever convenient to the operator, 90 not shown.

The derrick portion of the hoist is mounted in bearings 24 secured on top of the side members of the main frame 16 so as to allow 100 it to swing or oscillate backward or forward, as the case may require, and for a purpose which will hereinafter appear, the ends 25 of the squared shaft 26 being turned circular to permit of this swinging action.

105 The squared shaft 26 carries a casting or support 27 near its center upon which a sheave 28 is mounted to guide a chain or cable 29, and another sheave 30, serving a similar purpose, is mounted upon a shaft or 110

bolt 31 at the apex or upper end of the derrick 32. This upper end is shaped like an inverted **U** and provides a very appropriate housing between its sides for the 5 sheave 30. Below the housing just mentioned the derrick 32 spreads outward in the form of an inverted **V**, the lower ends being secured by rivets or bolts 33 to castings 34 supported by the squared shaft 26 in close 10 proximity to the bearings 24. This construction gives strength and rigidity combined with lightness, and distributes the strain of the load to be hoisted, to several points, all of which are very desirable features in structures of this nature.

One end of the chain or cable 29 is secured to the drum 22, and the other end to the front end of the body **B** of the truck, the rear end of the body being hinged to the 20 main frame as is customary and as shown at **H**. In hoisting the forward end of a body thus secured, it describes an arc with a tendency to recede or move away from the sheave 30, in proportion to the height to 25 which the body is raised. The swinging derrick, however, compensates for this receding action and entirely eliminates the consequent angular pull of the cable as the body approaches its upper limit, and the 30 forward swing of the lower extremity of the bottom sheave wheel 28 advances the cable leading to the drum 22 as the winding of the cable progresses, thereby preventing the cable from over-riding on the drum, as well 35 as maintaining proper alignment of the cable over and between the sheaves 28 and 30.

To operate the hoist, the gear shift lever 35 is placed in neutral position so as to 40 disconnect the engine from the truck driving mechanism. The clutch is then engaged by actuating the clutch pedal 36 in the usual manner. This rotates the countershaft 37 of the transmission and the reversing pinion 4.

45 The gear 3 will be thrown into engagement with the reversing pinion 4 against the tension of the coiled spring 7 by proper manipulation of the engaging lever 38. This com-

pletes the coupling, and the engine then 50 raises the front end of the body by its own power. When the body is raised to the desired height the brake band 23 is tightened and pressure on the engaging lever 38 is released, allowing the coil spring 7 to automatically kick gear 3 out of mesh with the reversing pinion 4 and maintaining it in 55 this position until another application is required. The body may be dropped whenever desired by simply easing up the brake band 23, allowing it to return to its normal position through no other power than its own weight.

From the foregoing it will be observed 60 that I have produced a power hoist which is novel, light and inexpensive, calculated to effect the accomplishment of the several objects stated; but while the present embodiment of the invention is believed at this time to be preferable I do not wish to limit myself to the structural details defined, as it 65 is obvious that many changes, modifications, and variations might be effected without departing from the scope of the protection claimed.

75 What is claimed is:

The combination with a truck including a transmission, a hinged body, and an upwardly extending derrick mounted to swing toward and from the body, of a drum supported beyond one side of the truck body, a 80 flexible connection between the drum and one end of the body, an internal gear revoluble with the drum, a gear meshing therewith, a spring restrained shiftable gear, means for transmitting motion from said 85 shiftable gear to the gear engaging the internal gear, and means under the control of the driver for moving the shiftable gear into mesh with a gear of the transmission.

In testimony that I claim the foregoing as 90 my own, I have hereto affixed my signature in the presence of two witnesses.

CYRENIUS LOSCH.
